Des. 201,856
Patented Aug. 3, 1965

201,856

CUSTOMER RESERVATION CABINET

Philip M. Evans, 119 W. Denny Way, Seattle, Wash.

Filed Oct. 21, 1963, Ser. No. 77,060

Term of patent 7 years

(Cl. D80—11)

Fig. 2.

Fig. 1.

Fig. 3.

The dominant features of my design reside in the portions shown in full lines.

I claim:

The ornamental design for a customer reservation cabinet, as shown and described.
